CLAIM

The ornamental design for an electronic camera, as shown and described.

DESCRIPTION

FIG. 1 is a top, front and right side perspective view of an electronic camera showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIG. 8 is a reduced top, front and right side perspective view thereof, shown in an alternate configuration wherein the camera is removed from the case and the case is shown in an open configuration.

The broken lines depict portions of an electronic camera in which the design is embodied that form no part of the claimed design.
